UNITED STATES PATENT OFFICE.

JOHN M. WEIR, OF EAST CLEVELAND, OHIO.

REMOVABLE HAND-RAIL STRUCTURE.

1,356,675.

Specification of Letters Patent. Patented Oct. 26, 1920.

Application filed December 15, 1919. Serial No. 344,825.

To all whom it may concern:

Be it known that I, JOHN M. WEIR, a citizen of the United States, residing at E. Cleveland, in the county of Cuyahoga and State of Ohio, have invented a certain new and useful Improvement in Removable Hand-Rail Structures, of which the following is a full, clear, and exact description.

This invention relates to a construction which is primarily adapted to serve as a removable hand rail for use with stairs in buildings, although as will be apparent as the description proceeds, the construction is adaptable for other use as well.

In many buildings such as apartment dwellings the stairways are rather narrow and usually steep, due to the desire of the builders to use their usually limited space in providing as large an area in the living rooms as possible.

Because the halls are narrow, hand rails in connection with stairs are almost universally dispensed with, although necessary where children or elderly persons must use the stairs.

But when a hand rail is used as a permanent fixture, it interferes with the moving of furniture up and down stairways because it subtracts a certain amount of valuable space.

One of the purposes of this invention is to provide a hand rail for use with stairs which is a stable and rigid structure when in position and may be used as hand rails are usually used, but on the other hand it may be readily removed so as to give the maximum amount of space which the stairway affords when necessity requires.

Not only is the removable hand rail a useful appurtenance to stairways in dwellings, but in factories and other buildings where usually as much space is desired as may be afforded when articles are moved up and down the stairway.

Reference should be had to the accompanying drawings forming a part of this specification in which Figure 1 illustrates in elevation, a stairway in connection with which the hand rail of my invention is used; Fig. 2 is an elevation with portions in section showing the engagement between a supporting member and the arm which co-operates therewith; Fig. 3 is an elevation of a portion of Fig. 2; Fig. 4 is a section on the line 4—4 of Fig. 3; Fig. 5 is a section on the line 5—5 of Fig. 3.

Referring to the drawings, 1 indicates a hand rail which is suitably secured to extending arms 2. These arms at their inner ends are adapted to be removably supported in a wall of the building and extend a suitable distance out from the wall to permit the hand of a passer to grasp and obtain support of the hand rail.

In order to obviate any extensions whatsoever, I construct the support which receives the arms 2 so that it may be depressed into the wall of the building and lie substantially flush with the wall of the building. Such a supporting member is indicated at 3 and comprises preferably a unitary structure or casing which has a front wall 4 that lies flush with the wall of the building. There is an inwardly extending box like part such as indicated at 5 and when the fixture just described is inserted in the wall the front face 4 is secured by use of screws extending through suitable openings such as indicated at 6. The front face 4 is provided with an opening such as indicated at 7, this opening being of any desired form and in the present instance is shown as substantially rectangular.

The inner end of the arm 2 is provided with an extension 2^a which in thickness is substantially the thickness between the front and rear wall of the opening 5 and the width of the extension 2^a is substantially the width between the side walls of the member 3 so that when the extension 2^a is in place within the member 3, there is a close fit which prevents rattling or undue movement. The arm 2 with its extension 2^a is inserted through the opening 7 in the manner indicated in dotted lines in Fig. 2 and when the arms are so inserted the arms and hand rail are definitely positioned with respect to the wall.

As will be seen, the hand rail and arms may be removed by slightly elevating the same and lowering the hand rail so as to permit the extensions 2^a for the arms 2 to slip out through the opening 7.

As will be apparent, various modifications of the structure disclosed may be made without departing from the spirit of the invention.

Having described my invention, I claim—

1. A removable hand rail structure comprising a hand rail proper, arms to which the hand rail is secured, each of said arms having an offset portion, supporting members

- affixed to a wall, each supporting member comprising a box like structure having a front wall with an opening therein, the offset portion of each arm extending into the box like structure and behind the front wall thereof and the portion of each arm adjacent the off-set part extending through the opening in the said supporting members.
- 10 2. A removable hand rail structure comprising a hand rail proper, arms to which the hand rail is secured, each of said arms being provided with an offset portion which extends at an angle with respect to the main portion of the arm, supporting members affixed to a wall, each of said supporting members comprising a box like structure having a front wall with an opening therein, the offset portion of each arm extending within the support and behind the front wall, the adjacent portion of the arm extending through the opening in the wall of the supporting member with which it is associated.
- 15 3. A removable hand rail structure comprising a hand rail proper, arms to which the hand rail is secured, each of said arms having an offset portion, supporting members affixed to the wall, each of said sup-

porting members having a front wall with an opening therein, the said front wall being flush with the wall to which the support is affixed, the offset portion of each arm extending within and behind the front wall of each supporting member with the adjacent portion of each arm extending through the opening in the front wall of the supporting member with which it is associated.

4. A removable hand rail structure comprising a hand rail proper, arms to which the hand rail is secured, each of said arms having an angular offset portion, supporting members affixed to the wall, each of said supporting members comprising a box like structure having a front and rear wall, the front wall of said supporting members being provided with an opening, the offset portion of each arm extending within a supporting member and fitting between the front and rear wall of the supporting member below the opening in said supporting member, the adjacent portion of each arm extending through the opening in the supporting member with which it is associated.

In testimony whereof I hereunto affix my signature.

JOHN M. WEIR.
